UNITED STATES PATENT OFFICE.

JOSEPH HOFFMAN, OF NEW YORK, N. Y., ASSIGNOR TO JOSEPH RECKENDORFER, OF SAME PLACE.

LEAD AND CRAYON HOLDER.

SPECIFICATION forming part of Letters Patent No. 240,712, dated April 26, 1881.

Application filed March 21, 1881. (No model.)

To all whom it may concern:

Be it known that I, JOSEPH HOFFMAN, of the city, county, and State of New York, have invented certain new and useful Improvements 5 in Lead and Crayon Holders, of which the following is a specification.

My invention has reference to that kind of lead and crayon holder in which the lead clamping or grasping device is caused to release the 10 lead by the movement of a pressure-cap on the end of the case or handle against the stress of a reacting spring, which spring, as soon as the cap is relieved from pressure, returns the parts of the holder to a position in which the lead- 15 clamp will close upon the lead. A lead or crayon holder of this kind is generally known in the market under the name of "automatic."

It is my object to make an extension-holder of this kind—that is to say, a holder whose 20 case or handle can be extended when the article is used, and which, when the article is not in use, can be shortened, so that it may be carried conveniently in the pocket, on a watch-chain, or otherwise. This I accomplish by 25 making an extension-piece of the pressure-cap, or that part which, as hereinbefore stated, when moved against the stress of the reacting spring, acts, through suitable intermediaries, to cause the lead-clamp to release the lead. 30 The tubular pressure-cap becomes one section of the sheath, the several sections of which telescope into one another, so that said sheath or handle may be lengthened or shortened, as desired.

35 The nature of my improvement, and the manner in which the same is or may be carried into effect, will be understood by reference to the accompanying drawings, in which—

Figure 1 is a perspective view of a holder 40 embodying my invention. Fig. 2 is a longitudinal central section of the same with the sheath contracted or shortened. Fig. 3 is a like section of the same with the sheath extended. Fig. 4 is a longitudinal central section of 45 a modified form of holder.

A is the tubular sheath or handle, provided with the usual tip or contracted nozzle, *a*.

B is the lead-containing tube, longitudinally movable with respect to the sheath, and terminating at its front end in jaws *b*, (constituting the lead-clamp in this instance,) which pro-

ject through the tip *a*, and are acted on by the latter when the tube is retracted to close upon the lead.

C is the retracting-spring, (arranged in this 55 instance near the front end of the sheath,) which encircles the tube, and is confined between an annular shoulder, *c*, on the tube and an annular washer, *d*, fixed in the tip *a*. A lip, *e*, on the tube in front of the washer *d*, 60 limits the rearward movement of the tube.

The parts thus far described are constructed and arranged substantially in accordance with reissued Letters Patent No. 8,967, of November 18, 1879, and Letters Patent No. 235,150, 65 of December 7, 1880, and resemble the like parts of one well-known form of automatic holder now in the market. The sheath A, however, is considerably shorter than the sheath 70 of the ordinary automatic, and is not surmounted by the ordinary pressure-cap. In lieu of the latter device I employ the combined pressure-cap and extension-piece D, which is a tubular stem closed at its upper or outer end, and fitting and adapted to slide back and forth in 75 the lower section, A, as one section of a telescope fits into the other. It has one or two annular guide or bearing ribs, *f*, on its inner end, to make a snug fit in the lower section, and the latter has its upper end contracted, 80 as shown at *g*, so as to prevent the entire withdrawal of the pressure-cap section D. When 85 the case is contracted the section D is pushed in, as shown in Figs. 1 and 2, until its closed outer end rests on the end of the lead-containing tube B, and when in this position the said section has capacity for still further movement in the same direction, as indicated in Fig. 2, so that it may push the tube forward against the stress of spring C far enough to permit 90 the jaws to expand sufficiently to release the lead. In this position it acts as a pressure-cap; but when drawn out, as indicated in Fig. 3, it becomes an extension of the part A and lengthens the sheath.

It is manifest that the arrangement of the 95 combined extension-piece and pressure-cap may be varied considerably, and that it can be made to operate on the tube when it is in its extended position, as well as when it is in 100 its other position.

In Fig. 4 the combined pressure-cap and

extension-piece fits outside, instead of inside, the lower section, A. In the holder represented in this figure the lettered parts indicate similar lettered parts in the preceding figures. 5 This holder to all intents and purposes, except as to the feature in which my improvement resides, is the same as that described in Fraser's Letters Patent No. 223,498, of January 13, 1880, and requires no further description here.

10 My improvement is susceptible of ready application to various forms of automatic holders—such, for instance, as represented in Letters Patent Nos. 223,512, 223,513, 225,379, 228,897, 235,122, 232,607, 234,084, and others.

15 I do not, therefore, restrict myself to the details herein shown in illustration of my improvement; but

20 What I claim, and desire to secure by Letters Patent, is—

1. In a lead and crayon holder, the combination, with the sheath, the lead-clamp, the

lead-clamp-operating mechanism, and the reacting spring, of a longitudinally-sliding combined extension-piece and pressure-cap mounted in or on the sheath, adapted to move the lead-clamp-operating mechanism against the stress of the reacting spring, and also to be adjusted back and forth in or on the sheath, so as to lengthen or shorten the holder, substantially as hereinbefore set forth.

2. In an automatic lead and crayon holder, a telescopic extension-sheath, the upper section of which contains the pressure-cap, which acts upon the mechanism that operates the lead-clamp to release the lead, substantially as hereinbefore set forth.

In testimony whereof I have hereinunto set my hand this 17th day of March, A. D. 1881.

JOSEPH HOFFMAN.
